METAL-CLAD SWITCHGEAR

Russell E. Frink, Forest Hills, and Paul Olsson, Penn Township, Allegheny County, Pa., assignors to Westinghouse Electric Corporation, East Pittsburgh, Pa., a corporation of Pennsylvania

Application December 20, 1954, Serial No. 476,164

12 Claims. (Cl. 200—50)

Our invention relates, generally, to metal-clad switchgear and, more particularly, to levering devices and interlocking mechanisms for metal-clad switchgear having removable circuit breaker units.

In metal-clad switchgear a drive-in or levering device is usually provided for mechanically moving the circuit breaker unit between the test or disconnected position and the operating or connected position within the cell or housing. Also, an interlocking mechanism is provided which cooperates with the levering device to prevent movement of the breaker unit between the test and the operating positions if the breaker is closed and to prevent closing the breaker when it is at any point between the test and the operating positions. The levering devices and interlocking mechanisms utilized previously have been somewhat complicated in structure. Furthermore, some of them have not functioned properly at all times.

An object of our invention is to provide a levering device having a small number of parts for moving a circuit breaker unit within a switchgear cell.

Another object of our invention is to provide for holding the circuit breaker unit in the test position in the cell.

A further object of our invention is to provide a simple and effective interlocking mechanism for a removable circuit breaker unit.

Still another object of our invention is to coordinate the closing mechanism, the levering device and the interlocking mechanism for a circuit breaker unit in controlling the operation of the circuit breaker and the movement of the breaker unit within the cell.

Other objects of our invention will be explained fully hereinafter or will be apparent to those skilled in the art.

In accordance with one embodiment of our invention, an interlocking link has one end connected to the breaker operating mechanism and the other end so engaging a levering device that operation of the levering device to move the breaker unit is prevented if the breaker is closed. Closing of the circuit breaker is prevented when it is at any point between the test position and the operating position in the cell. A spring-biased pin holds the levering device and the breaker unit in the test position and the operating position.

For a better understanding of the nature and objects of the invention, reference may be had to the following detailed description, taken in conjunction with the accompanying drawings, in which:

Fig. 1 is a view, partly in side elevation and partly in section, of a portion of a metal-clad switchgear structure embodying the principal features of the invention;

Fig. 2 is an enlarged view, in elevation, of the levering device and interlocking mechanism for the circuit breaker;

Fig. 3 is an enlarged view, in section, taken along the line III—III in Fig. 2; and

2

Fig. 4 is an enlarged view, in section, taken along the line IV—IV in Fig. 2.

Referring to the drawing, and particularly to Fig. 1, the structure shown therein comprises a portion of a metal-clad switchgear cell or housing 10 which may be constructed by securing sheet metal members 11 to angle frame members 12 in a manner well-known in the art. The cell structure may rest upon beams 9 disposed upon a suitable foundation. The cell 10 comprises a circuit breaker compartment 13, and may include a current transformer compartment 14, a bus compartment 15, and/or an out-going cable compartment 16. The various compartments are separated by partition members 17, 18 and 19.

15 A circuit breaker unit 21 is disposed in the breaker compartment 13 and may be moved horizontally into and out of the cell on wheels 22 which run on rails 23 disposed at the bottom of the cell. One form of circuit breaker and operating mechanism therefore, which may be used, is that disclosed in Findley, Ogg and Florschutz Patent No. 2,515,994, issued July 18, 1950. A hinged door 24 is provided at the front of the cell to permit the breaker unit to be withdrawn from the cell.

In accordance with the usual practice, the breaker 25 unit is provided with primary disconnecting contact members 25 which are disposed to engage stationary contact members 26 which are mounted inside insulating sleeves 27 disposed inside the cell 10. The disconnecting contact members may be of the type described in Patent No. 2,376,818 issued May 22, 1945, to M. J. Rubel and assigned to the Westinghouse Electric Corporation.

A drive-in or levering device is provided for mechanically moving the circuit breaker unit 21 between the operating or connected position and the test or disconnected position within the cell 10. In the present drawing, the circuit breaker unit is shown in the disconnected position. When the breaker unit is inserted to the connected or operating position the disconnecting contact members 25 engage the stationary contact members 26, thereby connecting the circuit breaker to power conductors 28 which are connected to the stationary contact members 26.

In the present structure the levering device comprises a pair of lever arms 31 which are secured to opposite ends of a horizontal shaft 32 rotatably mounted in the circuit breaker unit. The shaft 32 is driven by a combined interlocking and levering member 33 which is secured to the shaft 32 and operated by a handle rod or lever 34 in a manner which will be described more fully hereinafter. A roller 35 is provided at the end of each one of the lever arms 31 and is disposed in a raceway provided between angle members 36 and 37 which are secured to the side of the cell 10. Since a lever arm 31 and cooperating angle members are provided at opposite sides of the breaker unit a levering force is provided at both sides of the breaker unit.

It will be seen that when the shaft 32 is rotated to drive the arms 31 in a direction indicated by the arrow in Fig. 1, the rollers 35 move in the raceways between the members 36 and 37 which, as previously explained, are secured to the side of the cell structure, thereby drawing the circuit breaker unit into the cell to the connected position. When the shaft 32 is rotated in the opposite direction, force is provided through the arms 31 to move the breaker unit from the connected to the disconnected position shown in the drawings. As indicated by the broken lines, each roller moves through an angle slightly over 180 degrees during the movement of the breaker unit from the disconnected to the connected position and moves the breaker a distance approximately twice the length of the arms 31.

As shown more clearly in Fig. 2 the shaft 32 is mounted

in bearing plates 38 which are attached to frame members 39 of the breaker unit by bolts 41. The arms 31 may be welded or otherwise secured to the shaft 32. Likewise, the interlocking member 33 and a spacing washer 42 are welded to the shaft 32. The interlocking member 33 has three substantially equally spaced holes 43 therein for receiving one end of the handle rod 34. The shaft 32 may be rotated by inserting the rod 34 in one of the holes 43 and moving the rod through an arc as indicated in Fig. 1. The rod 34 may then be removed and inserted in another hole to rotate the shaft 32 still further. As previously stated, three holes are provided in the member 33 for the rod 34, thereby permitting three strokes or operations to be utilized in moving the breaker unit between the connected and the disconnected positions.

An interlocking link 44 has one end connected to an operating member 45 of the circuit breaker mechanism by means of a pin 46. The member 45 is preferably connected to a part of the closing mechanism for the circuit breaker which moves with the movable contact of the breaker, and it is pivotally mounted on a pin or shaft 47. As shown in Fig. 3 the member 45 moves through an arc between the "breaker open" and the "breaker closed" positions during closing of the contact members of the circuit breaker. Likewise, the member 45 moves from the "breaker closed" position to the "breaker open" position during opening of the circuit breaker. Thus, the interlocking link 44 is moved longitudinally during operation of the contact members of the circuit breaker. The longitudinal movement of the link 44 is permitted by an oblong opening 48 in the link through which the shaft 32 extends to support the other end of the link 44.

As shown in Fig. 4 one side of the interlocking member 33 has slots or grooves 51 and 52 disposed therein between raised surfaces 53 and 54. In the present instance the slot 51 is slightly wider than the slot 52.

The interlocking link 44 has a lug 55 on one side which is disposed to enter the slot 51 when the circuit breaker unit is in the disconnected position as shown in the drawings. As shown in Fig. 4, one side of the lug 55 engages a surface 56 of the raised portion 53 of the member 33, thereby preventing further rotation of the member 33 in a counterclockwise direction as shown in Fig. 4. Thus further rotation of the arms 31 in a clockwise direction as shown in Fig. 3 is prevented. A positioning pin 57, which is biased upwardly by a spring 58, has entered a notch 59 in the periphery of the member 33 to hold the shaft 32 in this position. The pin 57 is slidably mounted in a bracket 61 which is attached to the frame member 39 of the circuit breaker unit by means of bolts 62.

When the contact members of the circuit breaker are closed the lug 55 on the interlocking link 44 slides downwardly into the slot 51, thereby making it impossible to rotate the shaft 32 and the arms 31 to insert the breaker unit into the cell with the contact members of the circuit breaker closed, since the end of raised portion 54 will engage the lug 55 and prevent further rotation. In this position, the roller 35 or lever 31 is opposite the inner side 36 of the raceway which is longer than the outer side 37, so that the breaker unit is blocked from moving back into connected position in the cell, if one should try to do that without using the levering-in mechanism. It will be noted that if the shaft 32 is rotated in a counterclockwise direction as shown in Fig. 3 until the pin 57 enters a second notch 63 in the member 33 there will be practically no forward motion of the breaker unit into the cell, but the rollers 35 will have entered the raceways between the angle members 36 and 37, the arms 31 having been moved to a horizontal position. Thus the circuit breaker unit is held or latched in the test position by means of the stop pin 57 which has entered the notch 63. The fact that the rollers 35 then engage the outer side 37 of the raceway prevents ac-

idental movement of the breaker unit out of the cell.

In this position the contact members of the circuit breaker can still be closed because of the width of the slot 51 in the interlocking member 33 which permits the lug 55 to slide downwardly in the slot 51 without engaging the raised portion 54 of the interlocking member 33. This position of the circuit breaker unit may be considered the test position and the contact members of the circuit breaker may be closed in this position. If it is desired to make the test position and the disconnected position coincide, the slot 51 may be made the same width as the slot 52, thereby preventing closing the breaker except in the connected and the disconnected positions. In this case the notch 63 would be omitted from the member 33.

If the member 33 is rotated further in a clockwise direction as shown in Fig. 4, or a counterclockwise direction as shown in Fig. 3, the breaker unit is drawn into the cell by means of arms 31 and the roller 35 as previously explained. The closing of the contact members of the circuit breaker is prevented while the breaker unit is being moved between the test and the connected positions by the lug 55 on the interlocking link 44 engaging the circular surface 64 of the raised portion 54 of the interlocking member 33.

When the shaft 32 is rotated to its extreme position in which the lug 55 engages a surface 65 of the raised portions 53, the contact members of the circuit breaker can be closed since the lug 55 can slide downwardly into the slot 52. This is the connected or operating position of the circuit breaker unit. When the contact members of the circuit breaker are closed, rotation of the shaft 32 to move the breaker unit toward the disconnected position is prevented by the lug 55 engaging an end surface 66 on the raised portion 54 of the interlocking member 33. It is impossible to move the circuit breaker to separate the primary disconnecting contact members when the contact members of the circuit breaker are closed. Furthermore, it is impossible to close the contact members of the circuit breaker at any point between the test and the connected positions of the circuit breaker unit.

Position indicators 67 and 68 may be cast on one side of the interlocking member 33 to line up opposite a name plate on the frame and show whether the breaker is in the connected position, the latched-in test position, or the disconnected position in which the breaker may be rolled out of the cell. Additional notches 69 and 71 are provided in the periphery of the member 33 to hold the circuit breaker unit while the handle rod 34 is being changed from one hole 43 to another in the member 33. A notch 72 is provided for the pin 57 to hold the circuit breaker unit in the operating position.

The breaker unit may be provided with a secondary disconnecting device of the type disclosed in Haylord Patent 2,276,968, issued March 17, 1942. Thus, the necessary control circuits for controlling the operation of the circuit breaker mechanism may be established when the breaker unit is in the test position.

From the foregoing description, it is apparent that we have provided a levering device and an interlocking mechanism which cooperate to provide a mechanical means for removing and replacing a circuit breaker unit in a switch-gear cell and which prevents movement of the circuit breaker unit between the test and the connected positions when the contact members of the circuit breaker are closed. Furthermore, the closing of the breaker contact members is prevented when the circuit breaker unit is at any point between the test and the connected positions. The levering device and the interlocking mechanism are relatively simple in structure and are sufficiently strong to preclude breakage of the mechanism under reasonable usage.

Since numerous changes may be made in the above-described construction, and different embodiments of the invention may be made without departing from the spirit and scope thereof, it is intended that all matter contained

in the foregoing description or shown in the accompanying drawing shall be interpreted as illustrative and not in a limiting sense.

We claim as our invention:

1. In a switchgear structure in combination, a cell, a circuit breaker unit disposed in the cell, operating means for closing contact members of the breaker, a rotatable levering device for moving the breaker unit between connected and test positions in the cell, an interlocking link having one end connected to said operating means, the other end of said link being actuated by said operating means to engage the levering device to prevent movement of the breaker unit if the contact members of the breaker are closed, and stop means on the levering device engaged by said interlocking link to limit the rotation of the levering device.

2. In a switchgear structure in combination, a cell, a circuit breaker unit disposed in the cell, operating means for closing contact members of the breaker, a rotatable levering device for moving the breaker unit between connected and test positions in the cell, an interlocking link having one end connected to said operating means, the other end of said link engaging the levering device to prevent closing the contact members of the breaker by said operating means when the breaker unit is at any point between the connected position and the test position, and stop means on the levering device engaged by said interlocking link to limit the rotation of the levering device.

3. In a switchgear structure in combination, a cell, a circuit breaker unit disposed in the cell, operating means for closing contact members of the breaker, a rotatable levering device for moving the breaker unit between connected and test positions in the cell, an interlocking link having one end connected to said operating means, said link being actuated by said operating means to prevent movement of the breaker unit when the contact members of the breaker are closed, said link having means thereon engaging said levering device to prevent closing the contact members of the breaker when the breaker unit is at any point between the connected position and the test position, and stop means on the levering device engaged by said interlocking link to limit the rotation of the levering device.

4. In a switchgear structure in combination, a cell, a circuit breaker unit disposed in the cell, operating means for closing contact members of the breaker, a rotatable levering device for moving the breaker unit between connected and test positions in the cell, an interlocking link having one end connected to said operating means, said link being moved longitudinally by said operating means to engage the levering device to prevent operation of the levering device when the contact members of the breaker are closed, and said levering device having means thereon engaging said link to prevent closing the contact members of the breaker by said operating means while the levering device is being operated to move the breaker unit.

5. In a switch gear structure, in combination, a cell, a circuit breaker unit disposed in the cell, a pivoted operating lever for closing contact members of the breaker, a rotatable shaft having one or more arms secured thereto engageable with the cell to move the breaker unit between predetermined positions within the cell, levering means secured to the shaft for rotating the shaft, an interlocking link having one end attached to said operating lever and the other end movably supported by said shaft, said link being movable longitudinally by said operating lever to engage the levering means to prevent rotation of the shaft to move the breaker unit when the contact members of the breaker are closed.

6. In a switchgear structure, in combination, a cell, a circuit breaker unit disposed in the cell, a pivoted operating lever for closing contact members of the breaker, a rotatable shaft having one or more arms secured thereto engageable with the cell to move the breaker unit be-

tween predetermined positions within the cell, levering means secured to the shaft for rotating the shaft, an interlocking link having one end attached to said operating lever and the other end movably supported by said shaft, said link being movable longitudinally by said operating lever to engage the levering means to prevent operation of the levering means when the contact members of the breaker are closed, and said levering means having a raised portion thereon for engaging said link to prevent closing the contact members of the breaker while the breaker by said operating lever unit is being moved between said predetermined positions.

7. In a switchgear structure, in combination, a cell, a circuit breaker unit disposed in the cell, a pivoted operating lever for closing contact members of the breaker, a rotatable shaft having one or more arms secured thereto and engageable with the cell to move the breaker unit between predetermined positions within the cell, interlocking means secured to the shaft, an interlocking link having one end pivotally attached to said operating lever, said link having an oblong opening adjacent the other end, said shaft extending through said opening to support said other end of the link, and said link being movable longitudinally by said operating lever to engage said interlocking means and prevent movement of the breaker unit by rotation of said shaft when the contact members of the breaker are closed.

8. In a switchgear structure, in combination, a cell, a circuit breaker unit disposed in the cell, a pivoted operating lever for closing contact members of the breaker, a rotatable shaft having one or more arms secured thereto and engageable with the cell to move the breaker unit between predetermined positions within the cell, interlocking means secured to the shaft, an interlocking link having one end pivotally attached to said operating lever, said link having an oblong opening adjacent the other end, said shaft extending through said opening to support said other end of the link, said link being movable longitudinally by said operating lever to engage said interlocking means and prevent movement of the breaker unit by rotation of said shaft when the contact members of the breaker are closed, and blocking means on said interlocking means for engaging said link to prevent closing the contact members of the breaker by said operating lever while the breaker unit is being moved between said predetermined positions.

9. In a switchgear structure, in combination, a cell, a circuit breaker unit disposed in the cell, a pivoted operating lever for closing contact members of the breaker, a rotatable shaft having one or more arms secured thereto and engageable with the cell to move the breaker unit between predetermined positions within the cell, interlocking means secured to the shaft, an interlocking link having one end pivotally attached to said operating lever, said link having an oblong opening adjacent the other end, said shaft extending through said opening to support said other end of the link, said link being movable longitudinally by said operating lever to engage said interlocking means and prevent movement of the breaker unit by rotation of said shaft when the contact members of the breaker are closed, said interlocking means having spaced means thereon corresponding to said predetermined positions of the breaker unit, and spring-biased means engaging said spaced means to hold the breaker unit in said predetermined positions.

10. In a switchgear structure, in combination, a cell having spaced members therein, a circuit breaker unit disposed in the cell, a pivoted operating lever for closing contact members of the breaker, a rotatable shaft having two arms secured thereto and engageable with said spaced members in the cell to move the breaker unit between test and connected positions within the cell, an interlocking member secured to the shaft and having spaced slots therein corresponding to the test and the connected positions of the breaker unit, an interlocking link having

one end pivotally attached to said operating lever and an oblong opening adjacent the other end, said shaft extending through said opening to support said other end of the shaft, said link being movable into the slots in the interlocking member by the operating lever to prevent movement of the breaker unit by rotation of the shaft when the contact members of the breaker are closed, blocking means on said interlocking member for engaging said link to prevent closing the contact members of the breaker by said operating lever while the breaker unit is being moved between the test and the connected positions, said arms being movable by said shaft into a position between said spaced members in the cell to hold the breaker unit in the test position, a notch on the interlocking member corresponding to the test position of the breaker unit, and a spring-biased pin entering said notch to retain the shaft in the test position.

11. In a switchgear structure, in combination, a cell, a circuit breaker unit disposed in the cell, operating means for closing contact members of the breaker, a 20 rotatable levering device for moving the breaker unit between connected and test positions in the cell, inter-

locking means cooperating with said levering device to prevent movement of the breaker unit by rotation of the levering device if the contact members of the breaker are closed, and spring-biased means for releasably engaging the levering device to retain the breaker unit in the test position in the cell.

12. In a switchgear structure, in combination, a cell, a circuit breaker unit disposed in the cell, operating means for closing contact members of the breaker, a rotatable levering device for moving the breaker unit between predetermined positions within the cell, interlocking means cooperating with said levering device to prevent movement of the breaker unit by rotation of the levering device if the contact members of the breaker unit are closed, and spring-biased means for releasably engaging the levering device to retain the breaker unit in said predetermined positions.
